UNITED STATES PATENT OFFICE.

ARTHUR E. BLASHILL, OF DELAWARE, CANADA.

WIRE-FENCE-WEAVING MACHINE.

SPECIFICATION forming part of Letters Patent No. 655,189, dated August 7, 1900.

Application filed November 7, 1899. Serial No. 736,209. (No model.)

To all whom it may concern:

Be it known that I, ARTHUR E. BLASHILL, a subject of the Queen of Great Britain, and a resident of Delaware township, in the county 5 of Middlesex, in the Province of Ontario, Canada, have invented a certain new and useful Wire-Fence-Weaving Machine, of which the following specification, taken in connection with the accompanying drawings, forms a 10 full, clear, and exact description.

This invention relates to a portable machine for weaving cross-wires with the horizontal wires of wire fences for the purpose of strengthening them and holding the horizontal 15 wires in fixed relation to each other.

The object is to provide a machine which will be simple, strong, durable, inexpensive to manufacture, and efficient in practical use for rapidly, easily, neatly, and firmly securing 20 cross-wires with the horizontal wires of wire fences.

To attain the desired end my invention consists in the novel construction and combination of parts hereinafter described and 25 claimed.

Reference is had to the accompanying drawings, wherein—

Figure 1 is a front view of a machine embodying my invention. In this view the pivot-bar P and spacer-bar R are partly cut away and only the top and bottom and one intermediate horizontal fence-wire are shown. Fig. 2 is a plan view of same. In this view one of the arms S, which connects the pivot-bar P and spacer-bar R with the top and bottom fence-wires, is shown in dotted lines. Fig. 3 is a detail side elevation of the internal gear-wheel and pinion. Fig. 4 is a detail end view of the machine, partly in section, on the 35 line x x of Fig. 2. In this view the internal gear-wheel D and slotted beveled gear-wheel K are removed. Fig. 5 is a detail side view of the slotted beveled gear-wheel K and plate L on the line x x of Fig. 2; Fig. 6, a detail 40 side elevation of a portion of the spacer-bar, showing one of the adjustable spacers secured thereto.

In the accompanying drawings, A designates the frame of the machine, and B a handle secured thereto.

C designates a shaft, one end of which is rigidly secured to the frame A.

D designates an internal gear-wheel, which is held in place, supported by, and revolves perfectly free on said shaft C, and D' is a 55 crank-handle secured to the wheel D, which crank-handle forms one convenient means for operating said gear-wheel D.

E designates a shaft which is held in place, supported by, and revolves perfectly free in 60 the frame A, and to one end of said shaft E the toothed pinion F is rigidly secured in such a position as to engage with the teeth of the internal gear-wheel D, and to the other end of said shaft E the beveled gear-wheel G is 65 rigidly secured.

H designates a shaft which is held in place, supported by, and revolves perfectly free in the frame A and at right angles to the shaft E. This shaft H is provided with an enlarged 70 head H', to which the sleeved spindle I is secured, on which the ball of wire J is held and from which the cross-wire for the fence is supplied, and said head H' is formed with a flange H⁴, the ends of which at the channel H² are 75 beveled for the purpose which will be hereinafter set forth. H² designates a channel formed in said shaft H, and A' a narrow opening formed in the frame A and parallel with the shaft H. The channel H² extends throughout the whole length of the shaft H, and the opening A' extends throughout the whole 80 length of the side of the frame A for the purpose which will be hereinafter set forth.

K designates a beveled gear-wheel in which 85 the slot K' is formed, and said gear-wheel is rigidly secured to one end of the shaft H in such a position as to engage with the beveled gear-wheel G. L designates a plate which is rigidly secured to said beveled gear-wheel K, 90 and in said plate the recess L' and perforation L² are formed.

M designates a locking-arm which is pivoted on the frame A and provided with the angular end M', which end is fitted to and engages with a socket H³, formed in the flange H⁴ of the head H', and between said arm M and a stud A² on the frame A a coil-spring N is interposed.

O designates a bell-crank pivoted on the 100 handle B, and O' a strand of wire or other suitable material which connects one end of the bell-crank O with one end of the locking-arm M.

- P designates a pivot-bar, and R a spacer-bar, which are braced and firmly secured together, held parallel with one another, and connected to the top and bottom fence-wires 5 e by the laterally and vertically curved arms S S, and through openings in said arms the pivot-bar and spacer-bar project, so that said arms may be adjusted vertically on said bars P and R, and when properly adjusted are 10 rigidly held at that point by tightening the set-screws P' and R', respectively, and said arms S are provided with the flanges S', S², S³, S⁴ S⁵, S⁶, S⁷ and S⁸, and through said flanges cotter-pins S⁹ are projected. The upper arm S is 15 curved vertically upward above the top horizontal fence-wire, and the lower arm S is curved vertically downward below the bottom horizontal fence-wire, as shown in Fig. 1, and both arms are also curved laterally, as 20 shown by dotted line in Fig. 2, so that they will not interfere in any way with the adjustment of the sleeve T in proper position opposite the top and bottom horizontal fence-wires e.
- 25 R² designates a spacer which is adjustable on the spacer-bar R and is held at the position to which it is adjusted by the set-screw R³, and said spacer is provided with flanges R⁴, through which the cotter-pin R⁵ is projected, as shown particularly in Fig. 6.
- T designates a sleeve which is vertically and pivotally adjustable on the pivot-bar P, and between projections T', extending laterally from said sleeve, the frame A is pivotally 35 secured by the pivot-bolt A³, and the pivotal movement of the frame A toward the horizontal wire is limited by the flange A⁴ of the frame A engaging with the flange T² on the sleeve T.
- 40 a designates a bolt which extends through the flanges A⁴ and T² and encircling said bolt a, and between a nut b on the end of said bolt and the flange A⁴ a coil-spring c is interposed.
- 45 d d designates curved guides which extend outward from the frame A on each side of the opening A' for the purpose of guiding the horizontal wire into the opening A' and channel H².
- 50 e e designates the horizontal wires, and J' the cross-wire.
- f designates a flange formed on the frame A and with a curved face f' for the purpose which will be hereinafter set forth.
- 55 The machine is placed in position as follows: The arms S S are adjusted on the pivot-bar P and spacer-bar R until the upper and lower horizontal fence-wires e rest between the flanges S' S' and S³ S³ and between the 60 flanges S² S² and S⁴ S⁴, respectively. When so adjusted, by tightening the set-screws P' and R' the arms S S are securely held in this position; but if the cross-wire J' were to be woven with horizontal wires e, extending in 65 an inclined direction downward, the upper and lower horizontal fence-wires e should be

adjusted at the outer free ends of the arms S S, between the flanges S³ and S⁶ and between the flanges S⁴ and S⁸, respectively. Again, if the cross-wire J' were to be woven 70 with horizontal wires e, extending in an inclined direction upward, the upper and lower horizontal fence-wires e should be adjusted at the outer free ends of the arms S S, between the flanges S³ and S⁵ and between the 75 flanges S⁴ and S⁷, respectively, and when the horizontal wires e are placed between the proper flanges on the arms S S they are held between said flanges by the cotter-pins S⁹. The spacer-bar R is provided with a series of 80 spacers R², one for each horizontal wire e, one of which spacers is shown in detail in Fig. 6, and one of each of said spacers R² is adjusted on said spacer-bar R, opposite one of each of said horizontal wires e, until the 85 flanges R⁴ clasp the adjacent horizontal fence-wire e, when said spacers R² are held at the position to which they are adjusted on the spacer-bar R by tightening the set-screws R³ and the horizontal wires e are held between the flanges R⁴ by the cotter-pins R⁵. These spacers R² are for the purpose of holding the horizontal wires e properly spaced or the proper distance apart when weaving the cross-wire J' therewith. 95

The operation is as follows: After the machine has been pivotally secured by the sleeve T to the pivot-bar P the operator grasps the handle B to steady and the handle D' to operate the machine; but before it can be operated the free end of the bell-crank lever O must be adjusted toward the handle B to withdraw the angular end M' of the locking-arm M from the socket H³. When so adjusted, by rotating the handle D', the internal 100 gear-wheel D, pinion F, shaft E, beveled gear-wheels G and K, and shaft H with its enlarged head H' are also rotated, and they are rotated until the opening A' in the frame A, the channel H² in the shaft H, and socket K' 105 in the beveled gear-wheel K are in line with one another, as shown in Fig. 1. The machine is then adjusted opposite and toward the upper horizontal fence-wire e, and the latter is guided by the curved guides d to and passes 110 through the opening A' and into the channel H² and socket K'. The wire J' is then threaded through the channel H² in the shaft H and through the perforation L² in the plate L. The end of said wire J' is then held against the 115 horizontal fence-wire e. When so adjusted, by freeing the angular end M' of the locking-arm M from the socket H³ and rotating the internal gear-wheel D once the toothed pinion F, as well as the shafts E and H and beveled 120 gear-wheels G and K, are rotated three times, which wraps the cross fence-wire J' around the horizontal fence-wire e three times, and the cross-wire J' being held in the perforation L² and the horizontal wire e being in the recess L', adjacent thereto, the friction of the 125 wire J' passing through the plate L causes 130

said wire J' to be wrapped tightly around the horizontal fence-wire e to rigidly secure one to the other at this point, and just before the one revolution of the internal gear-wheel D is completed the free end of the bell-crank lever O is released and the angular end M' of the locking-arm M rides on the side of the flange H^4 until it comes opposite the socket H^3 , when it will be adjusted therein by the spring N . This prevents the further operation of the machine and regulates the number of times that the cross-wire J' is wrapped around the horizontal fence-wire e , and the ends H^5 and H^6 of the flange H^4 adjacent to the channel H^2 are beveled, as shown in Fig. 1, so that when said shaft H , together with its head H' and flange H^4 , is rotated the angular end M' of the locking-arm M would pass freely upon and over said ends without catching thereon, and thus avoid and completely prevent the angular end of the locking-arm M from engaging with any other part of the head H' except at the socket H^3 . The machine is then pivotally adjusted on the pivot-bar P , back from said cross-wire e , until the latter is free from the frame A and back far enough so that sufficient wire will be unwound from the ball J to extend across the space between two adjacent fence-wires e , when said machine is then adjusted longitudinally on said bar P until the opening A' of the frame A comes opposite the next horizontal wire e , when the operation hereinbefore described is repeated to wrap the cross-wire around the next horizontal wire, and so on, until the cross-wire J' is secured to the top and bottom and all the intermediate horizontal fence-wires, after which the wire J' is cut from the fence. The machine is then adjusted lengthwise on the horizontal fence-wires to the point at which it is desired to have the horizontal fence-wires again connected together by the cross-wire J' , when the operation hereinbefore described is repeated. As the frame A is drawn back from the horizontal fence-wire e the cross-wire J' , which has been rigidly secured to said horizontal fence-wire e , is given off the ball J , through the perforation L^2 in the plate L , and the friction of said wire J' passing through said plate L causes the frame A , pivoted on the bolt A^3 , to compress the spring c and adjust the curved face f' of the flange f to abut against the spacer-bar R , which acts as a fulcrum for said frame A , which, together with the yielding action of the spring c , enables the machine to be drawn back from the wire e with a steady even motion.

The result of this invention is that a simple, strong, durable, inexpensive, and efficient machine is provided for rapidly, easily, and neatly weaving or firmly securing the cross-wire J' with the horizontal fence-wire e to strengthen the latter and to hold them in fixed relation to each other.

65 I have found by experiment that the con-

struction herein shown and described gives the best results. At the same time, while I prefer the said construction, I do not wish to limit myself to the details thereof, as they may be modified in various ways without departing from the spirit of my invention.

Having thus described my invention, I claim—

1. In a wire-fence-weaving machine, the shaft, H , in which a channel, H^2 , is formed, and having an enlarged head, H' , provided with a flange, H^4 , in which a socket, H^3 , is formed, and beveled at its ends adjacent to said channel, H^2 , substantially as and for the purpose set forth. 70

2. In a wire-fence-weaving machine, the shaft, H , in which a channel, H^2 , is formed and having a head, H' , provided with a flange, H^4 , in which a socket, H^3 , is formed, and beveled at its ends adjacent to said channel, H^2 , 80 and means for supporting said shaft in which it rotates perfectly free, in combination with a locking-arm, M , provided with an angular end, M' , and means for engaging said angular end with and disengaging it from the head, H' , at the socket, H^3 , substantially as and for the purpose set forth.

3. In a wire-fence-weaving machine, the frame, A , the stationary shaft, C , the internal gear-wheel, D , revolving on said shaft, C , and 95 means for operating said internal gear-wheel, in combination with the shaft, E , the toothed pinion, F , rigidly secured to one end of said shaft, E , and meshing with the teeth of the internal gear-wheel, D , the beveled gear-wheel, G , rigidly secured to the opposite end of said shaft, E , the shaft, H , and beveled gear-wheel, K , rigidly secured thereto, and engaging with the beveled gear-wheel, G , substantially as and for the purpose set forth. 100

4. In a wire-fence-weaving machine, the frame, A , the stationary shaft, C , the internal gear-wheel, D , and means for operating the same, the shaft, E , the toothed pinion, F , rigidly secured to one end of said shaft, E , 110 and engaging with the teeth of the internal gear-wheel, D , the beveled gear-wheel, G , secured to the opposite end of said shaft, E , the shaft, H , the beveled gear-wheel, K , rigidly secured thereto, and engaging with the beveled gear-wheel, G , and the sleeved spindle, I , secured to the end of the shaft, H , in combination with the locking-arm, M , formed with an angular end, M' , and means for engaging the angular end of said arm with, and disengaging it from the shaft, H , or other operative part of the machine, substantially as and for the purpose set forth. 115

5. In a wire-fence-weaving machine, the frame, A , in which the opening, A' , is formed, the stationary shaft, C , the integral gear-wheel, D , and means for operating the same, in combination with the shaft, E , the toothed pinion, F , rigidly secured to one end of said shaft, E , and engaging with the internal gear- 125

130

wheel, D, the beveled gear-wheel, G, rigidly secured to the opposite end of the shaft, E, the shaft, H, formed with a channel, H², the beveled gear-wheel, K, formed with the slot, 5 K', secured to the shaft, H, and engaging with the beveled gear-wheel, G, and the sleeved spindle, I, secured to the end of the shaft, H, substantially as and for the purpose set forth.

6. In a wire-fence-weaving machine, the frame, A, in which an opening, A', is formed, the stationary shaft, C, the internal gear-wheel, D, and means for operating the same, in combination with the shaft, E, the pinion, F, secured to one end of said shaft, E, and 10 engaging with the internal gear-wheel, D, the beveled gear-wheel, G, secured to the opposite end of said shaft, E, the shaft, H, formed with a channel, H², the beveled gear-wheel, K, formed with the slot, K', secured to the 15 shaft, H, and engaging with the beveled gear-wheel, G, the plate, L, in which the recess, L', and perforation, L², are formed, the guides, L, secured to the frame, A, and the sleeved spindle, I, secured to the end of the shaft, H, 20 substantially as and for the purpose set forth.

7. In a wire-fence-weaving machine, the shaft, H, having an enlarged head, H', provided with a flange, H⁴, in which a socket, H⁸, is formed, and also formed with beveled ends, 25 H⁶, and, H⁶, in combination with the frame, A, the stud, A², formed thereon, the locking-arm, M, formed with angular end, M', the spring, N, interposed between the angular end, M', of said locking-arm, M, and said stud, 30 A², the bell-crank, O, pivotally mounted on said frame, A, the strand, O', connecting one end of the bell-crank, O, with the locking-arm, M, and the handle, B, substantially as and for the purpose set forth.

40 8. In a wire-fence-weaving machine, the pivot-bar, P, and means for supporting said bar, the sleeve, T, pivotally and vertically adjustable on said bar, P, in combination with the frame, A, pivotally secured to the sleeve, 45 T, and a spring applied to said frame, so that the latter will move pivotally in relation to said sleeve, with a steady, even motion, substantially as set forth.

9. In a wire-fence-weaving machine, the 50 pivot-bar, P, and means for supporting said bar, the sleeve, T, provided with the flange, T², and pivotally and vertically adjustable on said bar, P, in combination with the frame, A, provided with the flange, A⁴, and pivotally secured to the sleeve T, substantially as and for the purpose set forth.

10. In a wire-fence-weaving machine, the pivot-bar, P, and means for supporting said bar, the sleeve, T, provided with the flange, 60 T², and pivotally and vertically adjustable on said bar, P, in combination with the frame, A, provided with the flange, A⁴, and pivotally secured to the sleeve, T, and a spring applied to said frame so that the latter will 65 move pivotally in relation to said sleeve, with

a steady, even motion, substantially as set forth.

11. In a wire-fence-weaving machine, the pivot-bar P, and means for supporting said bar, the sleeve, T, pivotally and vertically adjustable on the said bar, P, and the frame, A, pivotally secured to the sleeve, T, in combination with the bolt, a, extending through the frame, A, and sleeve T, a nut, b, on the end of said bolt, and a coil-spring, c, encircling said bolt and interposed between said frame, A, and nut, b, substantially as and for the purpose set forth.

12. In a wire-fence-weaving machine, the pivot-bar, P, and means for supporting said bar, the sleeve, T, provided with the flange, T², and pivotally and vertically adjustable on the bar, P, and the frame, A, provided with a flange, A⁴, and pivotally secured to the sleeve, T, in combination with the bolt, 80 a, extending through said flanges, T², and, A⁴, a nut, b, on the end of said bolt, and a coil spring, c, encircling said bolt, a, and interposed between said nut, b, and the flange, A⁴, substantially as and for the purpose set 90 forth.

13. In a wire-fence-weaving machine, the pivot-bar, P, the spacer-bar, R, and means for supporting said bars, the spacers, R², adjustable longitudinally on said bar, R, and means for holding said spacers at the position to which they are adjusted, and for holding the wire in contact therewith, the sleeve, T, pivotally and vertically adjustable on said bar, P, and the frame, A, provided with the flange, f, and pivotally secured to the sleeve, T, in combination with the bolt, a, extending through the frame, A, and sleeve, T, a nut, b, on the end of said bolt, and a coil-spring, c, encircling said bolt and interposed between 105 said nut, b, and frame, A, substantially as and for the purpose set forth.

14. In a wire-fence-weaving machine, the pivot-bar P, the spacer-bar, R, and means for supporting said bars, the spacers, R², 110 longitudinally adjustable on said bar, R, and means for holding said spacers at the position to which they are adjusted on said bar, R, and for holding the wire in contact therewith, the sleeve, T, provided with the flange, T², 115 pivotally and vertically adjustable on the bar, P, and the frame, A, provided with the flanges, f, and, A⁴, and pivotally secured to the sleeve, T, in combination with the bolt, a, extending through said flanges, T², and, A⁴, the nut, b, on the end of said bolt, and a coil-spring, c, encircling said bolt, and interposed between said nut, b, and frame, A, 120 substantially as and for the purpose set forth.

15. In a wire-fence-weaving machine, the 125 pivot-bar, P, the spacer-bar, R, and the vertically and laterally curved arms, S, S, and means for engaging the horizontal wires, e, with said arms, in combination with the sleeve, T, pivotally and longitudinally ad- 130

justable on said pivot-bar, P, and the frame, A, substantially as and for the purpose set forth.

16. In a wire-fence-weaving machine, the pivot-bar, P, the spacer-bar, R, and the vertically and laterally curved arms, S, S, provided with flanges, and means for holding the horizontal wires, e, between said flanges, in combination with the sleeve, T, pivotally

and longitudinally adjustable on said pivot-bar, P, and the frame, A, substantially as and for the purpose set forth. 10

In testimony whereof I have signed in the presence of the two undersigned witnesses.

ARTHUR E. BLASHILL.
